UNITED STATES PATENT OFFICE.

HIPPOLYT SAURER, OF ARBON, SWITZERLAND.

DEVICE FOR CONTROLLING AND REGULATING THE THREAD TENSION IN SHUTTLES OF EMBROIDERING-MACHINES.

1,273,278.

Specification of Letters Patent. Patented July 23, 1918.

Application filed August 1, 1917. Serial No. 183,901.

To all whom it may concern:

Be it known that I, HIPPOLYT SAURER, a citizen of the Republic of Switzerland, residing at Arbon, Switzerland, have invented 5 certain new and useful Improvements in Devices for Controlling and Regulating the Thread Tension in Shuttles of Embroidering-Machines; and I hereby declare the following to be a full, clear, and exact description 10 of the invention, such as will enable others skilled in the art to which it appertains to make and use the same, reference being had to the accompanying drawings, and to letters or figures of reference marked 15 thereon, which form a part of this specification.

For the purpose of varying the thread tension in shuttles used in embroidery-machines it is necessary—as it is well known 20 to those skilled in the art—to adjust the pivoted clip acting upon a plate spring. Such an adjustment of the clip has been carried out hitherto by hand, so that its was quite impossible to give to a thread the exact 25 tension required and to adjust the thread tension of all shuttles used in one and the same machine in the same manner.

The object of this invention is to provide 30 a device for effecting the adjustment of the clip and thus the regulation of the thread tension in a mechanical manner and also automatically, so that any desired thread tension may be given to each single shuttle and an equal thread tension may be 35 imparted to all shuttles of an embroidery-machine.

To the attainment of these ends the tension 40 of the thread, guided from the thread hole of the shuttle to a device for drawing the thread out of the shuttle, is transmitted, against the action of an adjustable counter-force, to a member, which, when it is moved out of its position of rest corresponding to the normal tension of the thread by means 45 of a power transmitting system, effects a corresponding movement of a member governing the movement of the pivoted spring tensioning clip, so that each deviation from the normal tension of the thread causes such 50 a displacement of the clip, that the normal tension is restored.

This invention will now be more particularly described with reference to the ac-

companying drawings, which illustrate several constructional examples:

55

Figure 1 is a side view of a device which embodies the invention.

Fig. 2 is a vertical longitudinal section of this device.

Figs. 3 and 4 are horizontal sections on the lines A—A and B—B, respectively, of Fig. 1.

Figs. 5 and 6 are vertical sections on the lines C—C and D—D, respectively, of Fig. 1.

65

Figs. 7, 8, 8^a, 9, 10, 11, 11^a and 12 show details of this embodiment.

65

Fig. 13 shows a vertical longitudinal section of a second exemplification of the invention in which the device for drawing 70 the thread out of the shuttle is arranged between the latter and the device for controlling and regulating the thread tension.

Fig. 14 is a section on the line E—E of Fig. 13.

75

Fig. 15 is a side view of a third exemplification of the invention, in which the shuttle is arranged between the device for drawing the thread out of the shuttle and the device for controlling and regulating 80 the thread tension, and

Fig. 16 is a section on the line F—F of Fig. 15.

85

Similar numerals refer to similar parts throughout the several views.

The shuttle —a—, the thread tension of which is to be regulated, is fixed in a suitable manner in the casing 1 of the device. The thread —c— of the bobbin fitted in the shuttle —a— passes through the thread hole 90 —b— and over a guide pulley 2 from which it is led to a device adapted to draw the thread out of the shuttle —a—. This device comprises a wheel or button 3 having a roughened outer surface around which 95 is wound the end of said thread for the purpose of securing a drawing engagement. To a shaft 4 (Figs. 3 and 6) carrying wheel 3 are fixed a cam disk 5 and a wheel 6. The latter is driven from a suitable source of 100 power not shown on the drawings by means of a cord 7. The guide wheel 2 is loosely mounted on a horizontal arm 8 of a frame 9 (Fig. 5) adapted to pivot on adjustable screws 10 provided in the lateral walls of 105 casing 1. The arm 8 extends through a slot

11 (Fig. 5) of the casing 1. 12 is an eye provided on the lower horizontal arm of this frame 9. To this eye is hooked one end of a spring 13 the other end of which is fixed 5 to the casing 1 by means of a hook 14 (Fig. 2). To the frame 9 is fixed a second horizontal arm 15 provided with a forked end (Figs. 2, 3, 5), which is adapted to engage a vertical feed lever 16. The upper end 10 of this lever 16 constitutes a pawl 17, which is adapted to coöperate with the teeth of feed wheels 18 and 19. The teeth of the latter are directed in opposite directions. The lower part of the feed lever 16 is connected 15 by means of a pin joint to a double armed lever 20 pivotally mounted on a shaft 21 (Fig. 6) supported in the casing 1. One arm of this lever 20 carries a roller 22 coöperating with the cam disk 5 (Fig. 2). 20 This lever 20 has also an arm 23 connected to the casing 1 by means of a spring 24, so that the roller 22 is always forced to rest on the cam disk 5, while the feed lever 16 is normally kept in its position of rest, *i. e.*, 25 in a position where it is prevented from acting upon the feed wheels 18, 19.

On the shafts 25, 26, carrying these feed wheels are loosely mounted the toothed wheels 27, 28 (Fig. 3) rigidly connected to 30 said wheels 18 and 19 and adapted to mesh with teeth 29 of a rack 31 sliding in bearings 30. The rack 31 is also provided with a second series of teeth 32, meshing with a toothed sector 33, fixed to a vertical shaft 34 (Fig. 6) movably mounted in the casing 1. The lower end of this shaft 34 is provided with two fingers or projections 35 (Figs. 7, 8, 9) adapted to engage the pivoted clip *d*— of the shuttle *a*— in such a 40 manner that a rotation of the shaft 34 causes a rotation of the clip *d*— about its axis of rotation *d'*—.

The hereinbefore described device works as follows: The thread *c*— drawn off the 45 bobbin *c*— contained in the shuttle *a*— passes in the usual manner beneath the plate spring *f*— acted upon by the movable clip *d*— and then through the shuttle hole *b*— and from here it is fed, as already stated, over the roller 2 and the wheel 3 with which it may be engaged by winding 50 several times around the roughened surface. Upon the imparting of rotation to the wheel 6 by means of the driving cord 7 in the direction of the arrow *H*— shown in Figs. 1 and 2 rotation is also imparted to the shaft 4 and the wheel 3 by means of a device described more fully later on. The thread *c*— is then drawn from the shuttle hole *b*— and wound upon the wheel 3. The 55 tension of the thread *c*— has the tendency to move the guide wheel 2 together with the arm 8 movable in the slot 11 and the frame 9 toward the wheel 3. The 60 spring 13, however, tends to move the up-

per end of the frame 9 together with the arm 8 and the guide wheel 2 away from the wheel 3, and to prevent movement toward wheel 3. Upon the ratio of these two forces exerted by the thread *c*— and the 70 spring 13 depends now the manner of operation of the device. When these two forces are balanced, *i. e.*, when the thread tension is equal to the tension of the adjustable spring 13, which corresponds to the normal 75 tension of the thread, the forked arm 15 of the frame 9 keeps the feed lever 16 in its neutral position, so that its end 17 is prevented from acting upon the feed wheels 18, 19. In spite of the fact that during the 80 rotation of the wheel 6 the cam disk 5 fixed to the shaft 4 imparts to the lever 20 a rocking movement against the action of its spring 24, so that the feed lever 16 is reciprocated in a vertical direction, the latter 85 movement is thus prevented from exerting any influence upon any part of the power transmitting mechanism, and the shaft 34 is not influenced in any way. The position of the pivoted clip *d*— is not changed. 90 The tension of the thread *c*—, which had a normal value when the device started to work, remains therefore also unchanged.

As soon as the tension of the thread *c*— is, however, greater or smaller than the normal 95 tension (to which corresponds also the tension exerted by the spring 13), the feed lever 16 is moved in such a manner by means of the forked end of the lever 15 acting upon frame 9, that it is caused to engage one of the feed wheels 18, 19. When the tension of the thread is too great said feed lever 16, 17 acts upon the feed wheel 19, and when the thread tension is too small it acts upon the feed wheel 18. 105

In the first instance each rocking movement about the axis 21 imparted to the lever 20 by means of cam disk 5 and roller 22 causes an upward movement of the lever 16, 17, so that a feed movement corresponding to the pitch of wheel 19 is imparted to the latter in the direction of the arrow shown in Fig. 2. This causes the toothed rack 31 to move away from the cam disk 5, so that a partial rotation in a counter-clockwise direction is imparted to the sector 33 and shaft 34 (Figs. 3 and 4). Owing to this, the clip *d*— is turned in such a manner about its axis *d'*—, that the tension of the thread *c*— decreases. This movement of the clip *d*— and the decrease in the thread tension continue until the feed lever 16, 17 disengages the feed wheel 19, which occurs at the moment at which the thread tension is equal to the tension of the 115 spring 13; *i. e.*, equal to the normal tension. 120

When, on the other hand, the thread tension is at the beginning of the operation smaller than the tension of the spring 13, the feed lever 16, 17 is caused to engage the 130

- feed wheel 18, so that the latter is rotated in the direction of the arrow shown in Fig. 2. Owing to this, the toothed rack 31 provided with teeth 32 is moved toward disk 5, so that 5 the toothed sector 33 and the shaft 34 are moved in a clockwise direction (Figs. 3 and 4). The result of this is a movement of the clip —d— about its axis —d'— having the effect to increase the tension of the thread. 10 This action continues until the continually increasing thread tension is equal to the tension of the spring 13, *i. e.*, to the normal tension. As soon as this is the case the feed lever 16, 17 is caused to disengage the feed wheel 18, so that the shaft 34 is stopped and 15 no further adjustment of the clip —d— is effected. As the tension of the spring 13 can be adjusted, any desired normal tension may be given to the thread drawn out of the 20 shuttle —a—. In order that the tension of the spring 13 may be adjusted in a more exact manner I give to the hook 14 a U-shape and I provide on one of its ends a graduated scale 14''. The other end of this hook 14 is 25 screw threaded and guided in an adjusting nut 14', so that upon rotation of the latter any desired tension may be given to the spring 13. Scale 14'' indicates the tension given to the spring 13. For the purpose of 30 preventing an accidental rotation of the feed wheels 18, 19 and keeping them in a yielding manner in their momentary position, I provide said wheels with brake-springs 18', 19'. The shaft 34 is supported in a yielding manner 35 by means of a helical spring 34' for the purpose of facilitating the insertion of the fingers 35 into the shuttle —a—. The small hand wheel 36 fixed to the shaft 34 may be used to return the shaft 34, the toothed sector 33 and the shaft 31 by hand into the 40 starting position.
- As already stated, the whole device is driven from the wheel 6. In the embodiment shown this wheel 6 is loose on shaft 4 and it may be clutched to the latter by means 45 of any suitable device. The clutch device shown by way of example comprises a pawl carrier 37 rigidly connected to the shaft 4 and provided with a pivoted pawl 38. The 50 one end 38' of the pawl 38, which has the shape of a double armed lever, acts as a clutch-tooth and co-operates with recesses 39 of a clutch disk 40, which is rigidly connected to the driving wheel 6 and also 55 loosely mounted on the shaft 4. The other end 38'' of the pawl 38 acts as a stop and contacts with the upper arm 42 of a clutch lever 44 pivoted at 43 to the casing 1 and acted upon by a pressure-spring 45 which presses 60 the arm 42 into the path of the end 38'' of the lever 38. The pawl 38 is acted upon by a spring 41 which tends to cause the tooth 38' to mesh with the recesses 39 of the disk 40. The spring 45 is stronger than the 65 spring 41, so that the pawl 38 is normally prevented from coming into engagement with the disk 40, the driving wheel 6 being in this case not coupled to the shaft 4. When it is desired to start the device the clutch lever 44 is pressed down by hand till 70 the arm 42 releases the end 38'' of pawl 38, whereupon the spring 41 causes the end 38' of the pawl 38 to engage one of the recesses 39, so that the pawl carrier 37 and the shaft 4 are coupled to the driving wheel 6. Upon 75 a releasing of the clutch lever 44 the stop 38'' strikes, after a complete revolution of the pawl carrier 37, against the arm 42 and the device is uncoupled. If such an uncoupling is not desired, the lever 44 has only to 80 be pressed constantly down. As a rule, however, the thread tension can be regulated during a single revolution of the shaft 4.
- In carrying out the invention as illustrated in Figs. 13 and 14 the device for 85 drawing the thread out of the shuttle —a— is not arranged behind the latter, but between the tension regulating devices and the shuttle —a—. In this embodiment the device for drawing the thread out of the shuttle —a— comprises two rollers 50, 51 mounted on pins fixed on the casing 1. This device comprises further a roller 52 mounted on a lever 53. The lever 53 is adapted to pivot about a fixed axis 54 and 90 it carries at its other end a roller 55 engaging a cam groove 56 of a disk 57 fixed to the shaft 4. It will be seen that upon a rotation of the shaft 4 a rocking movement is imparted to the lever 53, which during the 95 downward movement of its left hand end draws thread out of the shuttle —a—. For the rest the construction and manner of operation of this embodiment correspond to the construction and working of the first 100 exemplification.
- In the third embodiment of the invention, illustrated in Figs. 15 and 16, the shuttle —a— has a reciprocating movement, it being arranged, so to speak, between the device 110 for controlling the thread tension and the device for drawing the thread out of the shuttle —a—. This last mentioned device consists principally of a movable plate 60 guided by means of two pins 61 fixed in the 115 casing 1 and projecting through a longitudinal slot 62 of this plate 60. The latter is also provided with a pin 63 engaging a groove 64 of a cam disk 65 fixed to the shaft 4. The shuttle —a— may be secured 120 to the plate 60 by means of three projections 66. The toothed wheels 27 and 28 rigidly connected to the feed wheels 18 and 19, respectively, are adapted to mesh with a toothed wheel 67 fixed on a shaft 68, which carries also a skew gear 69. This skew gear 69 meshes with a skew gear 70 fixed to a shaft 71^a on which is keyed slidably a bevel wheel 71, carried by an arm of the plate 60 and adapted to mesh with a bevel wheel 72. 130

fixed to the shaft 34 which is provided on its lower end with the two fingers 35 for adjusting the clip —d—.

The thread —c— passing through the hole 5 —b— of the shuttle —a— is fixed to a lateral extension of the frame 9. It will be seen that a rotation of the shaft 71^a brought about by one of the feed wheels 18, 19, causes a rotation of the shaft 34 and therefore an 10 adjustment of the clip —d—.

The hereinbefore described devices for controlling and regulating the thread tension may be used in connection with any kind of shuttles for embroidery-machines 15 provided with a transverse clip for regulating the thread tension. In order to attain, however, a proper working it is preferred to provide the shuttles with a clip having a special shape (Figs. 8 and 10). The clip

20 —d— which is pivoted in the usual manner on a pin —d'— is provided with a prolongation —g—. The latter is engaged in such a manner by the fingers 35 (Fig. 7) of the shaft 34, that the axis of the shaft 34 is in 25 line with the axis of rotation —d'— of the clip —d—. According to the construction shown in Fig. 10 the prolongation —g— of the clip —d— is provided with a round hole —h—. In this case the shaft 34 is not pro-

25 vided with two fingers or claws 35 but with a round eccentric finger 35' (see Fig. 11, showing a bottom view, and Fig. 12) adapted to engage the hole —h— of the prolongation —g— of the clip —d—. Also in this 30 case the axis of the shaft 34 coincides with the axis of rotation —d'— of the clip —d—. Instead of having such a pin the shaft 34 may also be provided with a hole 34' adapted to be engaged by a pin 35'' (Fig. 11^a) on 35 the prolongation —g— of the clip —d—.

What I claim now as my invention is:

1. In a device of the character described, in combination, means for securing the shuttle in a determinate position, a device 45 for drawing the thread out of the shuttle, a movable member, adjustable means adapted to exert a variable tension upon this member to which is also transmitted the tension of the thread drawn out of the shuttle, a sec- 50 ond movable member adapted to control the position of the clip acting upon the shuttle spring beneath which passes the thread drawn out of the shuttle and motion transmitting means adapted to impart a move- 55 ment to this last mentioned movable member for the purpose of adjusting the position of the shuttle clip when said first mentioned member is moved out of its position of rest corresponding to the normal tension of the 60 thread, so that each deviation from the normal tension of the thread causes an adjustment of the shuttle clip.

2. In a device of the character described, in combination, means for securing the 65 shuttle in a determinate position, a driving

shaft, a device operatively connected to this shaft for drawing the thread out of the shuttle, a roller, a pivoted member carrying this roller over which is fed said thread drawn out of the shuttle, a spring acting 70 upon said pivoted member, the tension of the spring acting in the opposite sense upon this member as the thread tension, means for adjusting the tension of said spring, a second movable member adapted to control 75 the position of the clip acting upon the shuttle spring beneath which passes the thread drawn out of the shuttle and motion transmitting means imparting a movement to the movable member causing an adjustment of the shuttle clip upon a movement of said pivoted member out of its position of rest corresponding to the normal tension of the thread, each deviation from the normal tension of the thread causing thereby such 80 an adjustment of the shuttle clip, that the normal tension is restored in the thread drawn out of the shuttle.

3. In a device of the character described, in combination, means for securing the 90 shuttle in a determinate position, a driving shaft, a roller provided with a roughened surface fixed to this shaft and adapted to draw the thread out of the shuttle, a frame adapted to oscillate about a horizontal axis, 95 a roller carried by this frame, the thread drawn out of the shuttle being fed over this roller, a spring connected to the lower end of this frame, means for adjusting the tension of the spring, the tension of the latter acting 100 in the opposite sense upon this frame as the tension of the thread, so that the momentary position of the frame is determined by the ratio between the tensions of the spring and the thread, a movable member adapted to 105 control the position of the clip acting upon the shuttle spring beneath which passes the thread drawn out of the shuttle and motion transmitting means imparting a movement to the movable member causing an adjustment of the shuttle clip upon a movement of said frame out of its position of rest, which corresponds to the normal tension of the thread.

4. In a device of the character described, 115 in combination, means for securing the shuttle in a determinate position, a driving shaft, a roller provided with a roughened surface fixed to this shaft and adapted to draw the thread out of the shuttle, a frame adapted 120 to oscillate about a horizontal axis, a roller carried by this frame, the thread drawn out of the shuttle being fed over this roller, a spring connected to the lower end of this frame, means for adjusting the tension of this spring, the tension of the latter acting in the opposite sense upon this frame as the tension of the thread, so that the momentary position of the frame is determined 125 by the ratio between the tensions of the 130

- spring and the thread, a forked arm provided on said frame, a feed lever engaged by this arm, means for imparting to this lever an upward and downward movement, 5 two feed wheels, the feed lever being, according to the position of the frame, either in a position of rest or adapted to engage one of these two feed wheels, a movable shaft adapted to control the position of the 10 clip acting upon the shuttle spring beneath which passes the thread drawn out of the shuttle and means adapted to transmit the movement of said feed wheels to this movable shaft.
- 15 5. In a device of the character described, in combination, means for securing the shuttle in a determinate position, a driving shaft, a roller provided with a roughened surface fixed to this shaft and adapted to draw the 20 thread out of the shuttle, a frame adapted to oscillate about a horizontal axis, a roller carried by this frame, the thread drawn out of the shuttle being fed over this roller, a spring connected to the lower end of this 25 frame, means for adjusting the tension of this spring, the tension of the latter acting in the opposite sense upon this frame as the tension of the thread, so that the momentary position of the frame is determined by 30 the ratio between the tensions of the spring and the thread, a forked arm provided on said frame, a feed lever engaged by this arm, a pivoted lever connected at one end to said feed lever and carrying at its other 35 end a roller, a cam disk fixed to said driving shaft and adapted to act upon this roller, two feed wheels, the feed lever being, according to the position of the frame, either in a position of rest or adapted to 40 engage one of these two feed wheels, a movable shaft adapted to control the position of the clip acting upon the shuttle spring beneath which passes the thread drawn out of the shuttle and means adapted to transmit 45 the movement of said feed wheels to this movable shaft.
6. In a device of the character described, in combination, means for securing the shuttle in a determinate position, a driving shaft, 50 a roller fixed to this shaft and adapted to draw the thread out of the shuttle, a frame adapted to oscillate about a horizontal axis, a roller carried by this frame, the thread drawn out of the shuttle being fed over this 55 roller, a spring connected to the lower end of this frame, means for adjusting the tension of this spring, the tension of the latter acting in the opposite sense upon this frame as the tension of the thread, so that the 60 momentary position of the frame is determined by the ratio between the tensions of the spring and the thread, a forked arm provided on said frame, a feed lever engaged by this arm, means for imparting to 65 this lever an upward and downward move- ment, two feed wheels, the feed lever being, according to the position of the frame, either in a position of rest or adapted to engage one of these two feed wheels, two toothed wheels, each of the latter being 70 rigidly connected to one of said feed wheels, a toothed rack adapted to coöperate with said toothed wheels, a shaft, a toothed sector on this shaft adapted to mesh with said rack and means on this shaft adapted to control 75 the position of the clip acting upon the shuttle spring beneath which passes the thread drawn out of the shuttle.
7. In a device of the character described, in combination, means for securing the shuttle in a determinate position, a driving shaft, 80 a wheel loose on this shaft, a source of power driving said wheel, means adapted to couple said wheel to the driving shaft, a device operatively connected to this shaft for drawing the thread out of the shuttle, a roller, a pivoted member carrying this roller over which is fed said thread drawn out of the shuttle, a spring acting upon said pivoted member, the tension of the spring acting in 85 the opposite sense upon this member as the thread tension, means for adjusting the tension of said spring, a second movable member adapted to control the position of the clip acting upon the shuttle spring beneath 90 which passes the thread drawn out of the shuttle and motion transmitting means imparting a movement to the movable member causing an adjustment of the shuttle clip upon a movement of said pivoted member out of its position of rest corresponding to the normal tension of the thread, each deviation from the normal tension of the thread causing thereby such an adjustment of the shuttle clip, that the normal 95 tension is restored in the thread drawn out of the shuttle.
- 100 8. In a device of the character described, in combination, means for securing the shuttle in a determinate position, a driving shaft, 105 a source of power, a wheel loose on this shaft and driven by this source of power, a coupling disk connected to said wheel, a coupling pawl fixed to said driving shaft, a second pawl controlling the movement of 110 said first mentioned pawl, a spring acting upon this second pawl, a device operatively connected to said driving shaft for drawing the thread out of the shuttle, a roller, a pivoted member carrying this roller over which 115 is fed said thread drawn out of the shuttle, a spring acting upon said pivoted member, the tension of the spring acting in the opposite sense upon this member as the thread tension, means for adjusting the tension of 120 said spring, a second movable member adapted to control the position of the clip acting upon the shuttle spring beneath which passes the thread drawn out of the shuttle and motion transmitting means imparting 125 130

- a movement to the movable member causing an adjustment of the shuttle clip upon a movement of said pivoted member out of its position of rest corresponding to the normal 5 tension of the thread, each deviation from the normal tension of the thread causing thereby such an adjustment of the shuttle clip, that the normal tension is restored in the thread drawn out of the shuttle.
10. 9. In a device of the character described, in combination, means for securing the shuttle in a determinate position, a driving shaft, a device operatively connected to this shaft for drawing the thread out of the shuttle, a 15 roller, a pivoted member carrying this roller over which is fed said thread drawn out of the shuttle, a spring acting upon said pivoted member, the tension of the spring acting in the opposite sense upon this member 20 as the thread tension, means for adjusting the tension of said spring, a movable shaft, fingers on the lower end of this shaft adapted to engage a prolongation of the clip acting upon the shuttle spring beneath which 25 passes the thread drawn out of the shuttle and motion transmitting means imparting a movement to the shaft provided with said fingers causing an adjustment of the shuttle clip upon a movement of said pivoted 30 member out of its position of rest corresponding to the normal tension of the thread, each deviation from the normal tension of the thread causing thereby such an adjustment of the shuttle clip, that the normal tension is restored in the thread drawn out of the shuttle.
10. In a machine for adjusting the pressure of the thread tension springs of shuttles, in combination, means to support a 40 shuttle, means to draw out thread from the shuttle, means external to the shuttle to vary the pressure on the thread tension spring of the shuttle, and devices also external to the shuttle and controlled by the tension of the thread to operate said last named means.
11. In a device of the character described, in combination, means to support a shuttle, means to draw out thread from the shuttle, means to vary the pressure on the thread 50 tension spring of the shuttle, transmission devices to operate said last named means in one direction or the other, to increase or decrease the pressure on the thread tension spring, and including oppositely acting 55 gears, a continuously operating actuator normally out of operative relation with both of said gears, and means controlled by the tension of the thread to move said actuator into operative relation with one or the other of 60 said gears.
12. In a device of the character described,
- in combination, means to support a shuttle, means to draw out thread from the shuttle, means to vary the pressure on the thread tension spring of the shuttle, transmission devices to operate said last named means in one direction or the other, to increase or decrease the pressure on the thread tension spring, and including oppositely acting gears, a continuously operating actuator normally out of operative relation with both of said gears, a pivoted frame engaging said actuator and adapted to move the same into operative relation with one or the other of said gears, said frame being subject to the tension of the thread in one direction, and a spring connected to the frame to move the same in opposition to the tension of the thread.
13. In a device of the character described, in combination, means to support a shuttle, means to draw out thread from the shuttle, a movable member subject to movement in one direction by the tension of the thread, means tending to move said member in the opposite 85 direction, means to vary the pressure on the thread tension spring of the shuttle, and transmission devices controlled by the position of said movable member to operate said last named means in one direction or the 90 other.
14. In a device of the character described, in combination, means to support a shuttle, means to draw out thread from the shuttle, a movable member subject to movement in one 95 direction by the tension of the thread, means tending to move said member in the opposite direction, means to vary the pressure on the thread tension spring of the shuttle, transmission devices to operate said last named 100 means in one direction or the other and including oppositely acting gears, and an actuator normally out of operation with both of said gears and adapted to be moved by said movable member into operative relation with one or the other of said gears.
15. In a device of the character described, in combination, means to support a shuttle, means to draw out thread from the shuttle having a guide wheel about which the thread 110 passes, a spring applied to the movable member to move the same in opposition to the tension of the thread, means to vary the pressure on the thread tension spring of the shuttle, and transmission devices operated 115 by the position of said movable member to operate said last named means in one direction or the other.

In testimony that I claim the foregoing as my invention, I have signed my name.

HIPPOLYT SAURER.
